FILLING SPOUT

Filed Jan. 25, 1928

INVENTOR:—
MILTON R. HOLBERT
By Martin P. Smith,
ATTY.

UNITED STATES PATENT OFFICE.

MILTON R. HOLBERT, OF SAN PEDRO, CALIFORNIA.

FILLING SPOUT.

Application filed January 25, 1928. Serial No. 249,279.

My invention relates to a filling spout that is especially designed for use on the hose or flexible tubes that are now in general use for dispensing or delivering liquids from a supply tank to containers, and the particular embodiment of the invention herein illustrated and described is especially applicable for use on the hose or flexible tube utilized for delivering gasoline to the tanks 10 of automobiles.

The principal objects of my invention are to generally improve upon and simplify the construction of the existing forms of filling spouts, to provide a device of the character referred to that will automatically cut off the supply of liquid when the receptacle into which the liquid is being delivered becomes full, or reaches a predetermined level, and which arrangement enables the attendant 20 or person dispensing the liquid to place the nozzle in the tank and then attend to other duties, with the assurance that the flow of liquid will be cut off before the receptacle overflows.

A further object of my invention is to provide a filling spout of the character referred to and to arrange thereon means whereby the valve that controls the flow of liquid thru the spout may be, by manual 30 operation, permitted to close at any desired time during the flow of liquid thru the spout, thus enabling the flow of liquid to be very accurately regulated and controlled.

Further objects of my invention are to provide an automatically acting filling spout that is relatively simple in construction, inexpensive of manufacture and which will be very effective in performing the functions for which it is intended.

With the foregoing and other objects in view, my invention consists in certain novel features of construction and arrangement of parts that will hereinafter be more fully described and claimed and illustrated in the accompanying drawing, in which—

Fig. 1 is a top plan view of a filling spout of my improved construction.

Fig. 2 is a vertical section taken lengthwise thru the approximate center of the spout and showing the parts thereof set so as to permit liquid to flow thru the spout.

Fig. 3 is a horizontal section taken approximately on the line 3—3 of Fig. 2.

Fig. 4 is an enlarged detail section taken approximately on the line 4—4 of Fig. 2.

Referring by numerals to the accompany-

ing drawings which illustrate a practical embodiment of my invention, 10 designates the body of the spout which is in the form of a tube and extending downwardly and outwardly from the forward end of the tubular body 10, is a tubular member 11 that is adapted to be inserted in the filling nipple or opening in the tank of receptacle that is to receive the liquid that passes thru the 65 spout.

The rear end of the tubular body 10 is adapted to be connected to a hose or flexible tube, (not shown).

Arranged within the tubular body 10 is a 70 partition 13 having a port 14, the edge of which is tapered to form a valve seat and adapted to rest on said seat and to control the flow of liquid thru the spout, is a downwardly opening spring-held valve 15 that 75 is carried by a stem 16.

Formed in the lower portion of the body 10, immediately below the port 14, and valve 15, is an opening 17 that is normally closed by a screw cap or plug 18.

The upper portion of valve stem 16 extends thru a gland or stuffing box 19 in the top of the body 10 and the upper end of said valve stem is adapted to bear against the underside of a short hand lever 20 that is 85 positioned above the tubular body 10, and the forward end of which lever is pivotally connected to an inverted U-shaped guard 21 that is formed integral with the forward end of the body 10 and the upper end of 90 the tubular member 11.

Guard 21 is provided with an aperture 22 which enables the spout to be suspended on a hook or the like while not in use. Formed in the lower portion of tubular member 11, 95 is a conical partition 23, and formed thru the wall of said member 11, immediately above this partition, is a series of apertures 24, which serve as openings for the liquid that passes thru the spout.

The inner or rear portion of the depending tubular member 11 is provided with a series of spaced notches 11^a, any one of which is adapted to receive the flange on the upper end of the filling nipple of a gasoline tank 105 and thus, the position of the lower end of the spout 11 relatively to the top of the tank in which said spout is positioned, may be regulated.

Formed integral with the end of the conical partition 23, is a tubular member 25 that extends axially upward thru the upper

- portion of member 11 and thru the top thereof, and surrounding the upper portion of this tubular member is a concentric wall 26 that is formed integral with said tubular member 25 and with the top of the member 11 and the lower portion of the annular chamber 27, between said wall 26 and tubular member 25, serves as a pocket for an expansive coil spring 28.
- 10 Arranged to slide freely upon the upper portion of the tubular member 25 and within the upper portion of chamber 27, is a short sleeve or collar 29 provided on its upper edge with an outwardly projecting 15 V-shaped flange 30, and which sleeve or collar is normally urged upward under the influence of spring 28.

Arranged to slide freely thru tubular member 25, is a rod 31, the lower end of 20 which carries a float 32 and which latter, occupies a position in the lower portion of tubular member 11 below the partition 23 therein.

Pivotal mounted on a lug 33 that is 25 formed on top of tubular member 11, is a dog or pawl 34, the point of which is adapted to engage over the edge of the V-shaped flange 30 on the sleeve or collar 29 to retain the latter in its lowermost position when the 30 device is set for use, and secured to and projecting upwardly from the rear end of this pawl is a flat spring 35, and formed integral with and projecting forwardly from the upper end of this spring, is a pair of pins 36 35 that extend thru loops or eyes 37 and the latter projecting upwardly from a small collar 38 that is arranged for sliding movement on the upper portion of tubular member 25, and which upper portion is slightly 40 reduced in diameter, thus forming a shoulder 39 on the tubular member between the collars 30 and 38.

Arranged on the reduced portion of the tubular member 25 and resting on the shoulder 39, is the lower end of a small coil spring 40, the upper end thereof bearing against the underside of collar 38.

Pivotal mounted on the inner face of the front portion of guard 21 is a dog 41, the 50 free end of which is adapted to engage over a flange 42 that is formed on the upper edge of collar 38, and projecting upwardly from the rear end of dog 41, is a spring arm 43. Projecting rearwardly from the upper 55 end of this spring arm are fingers 44, that are spaced apart so as to occupy positions to the sides of the upper portion of rod 31 and said fingers are slotted as designated by 45, in order to receive the ends of a pin 46 that 60 is seated in said rod 31. An arm or lever 47 is positioned between the tubular body 10 and handle 20, and the forward end of this arm is forked or bifurcated so that it straddles the lower portion of the guard 65 21 and the arms formed by the bifurcation

of the forward end of the lever are adapted to bear on top of the collar 29.

The intermediate portion of the arm or lever 47 is provided with a loop 48 for the accommodation of the valve stem 16 and to 70 the rear of this loop, the arm or lever is provided with trunnions 49 that are journaled in suitable anti-friction bearings 50, preferably with ball type.

The rear end of the arm 47 terminates below the rear end of handle 20 and the rear portion of said arm bears against the inclined face 52 that is formed on the upper portion of a hook 53 which latter is pivotally connected to its upper end to the rear portion of handle 20. Arranged behind the hook 53, and normally urging the same toward the arm 39, is a spring 54.

When handle 20 carrying hook 53 is moved downward to its limit of movement, said 85 hook 53 engages beneath a hook 55 which latter is fixed on top of the tubular body 10 and when these two hooks are engaged, the operating parts of the spout are in set position, as illustrated in Fig. 2.

Mounted for vertical movement thru the rear portion of handle 20, is a springheld pin or plunger 56 and which latter, when moved downward, engages and bears downwardly upon the rear end of arm 47 (see 95 Fig. 4).

Journaled in bearings 57 that are formed on top of the bifurcated forward end of lever 47 are rods 58, the forward ends of which are bent inwardly so as to overlie the 100 top of collar 38 and the rear ends of said rods are bent inwardly and terminate adjacent to each other at a point directly above the longitudinal center of arm 47. Arranged for sliding movement thru the forward portion of handle 20 is a springheld pin or plunger 59, the lower end of which is adapted to engage on top of the inturned rear ends of the rods 58, and to move the same and the forward portion of arm or 110 lever 47 downwardly when pressure is applied to the top of said pin or plunger.

When the parts of the filling nozzles are set for use, or the nozzle is opened to permit the flow of fluid therethru, handle 20 is 115 moved downward until hook 53 engages hook 55, thus locking the handle in its depressed position, and as the handle is thus moved downward, the valve stem 16 will be engaged and moved downward, thereby unseating the valve 15 so as to permit fluid to flow thru the nozzle.

As handle 20 is moved downward, plunger 59 is simultaneously pressed downward and the lower end thereof engages the inturned rear ends of the rods 58, thereby locking the latter and causing the inturned ends of said rods to bear on collar 38 and move the same downward against the resistance offered by spring 40, and said collar 38 is thus 125 13

10 moved downward until the inner end of dog 41 engages over the edge of flange 42.

As plunger 59 is thus moved downward to lock the rods 58, the arm or lever 47 will be swung on its fulcrum, the bearings 50, so that the bifurcated forward end of said arm will bear downwardly on top of collar 29 and force the same downward into the upper portion of chamber 27, thereby compressing spring 28 which is considerably stronger than spring 40. As collar 29 is thus moved downward, the inner end of dog 34 will engage over the edge of flange 30, and thus, the two collars 38 and 29 will be retained in set position by the dogs 41 and 34 and said dogs will be retained in their positions by the weight of the float 32 and rod 31, which latter is connected to dog 41 by means of the pin 46, the slotted fingers 20 44, and spring 43.

When the forward end of lever 47 is moved downward as just described, the rear end of said lever will be elevated slightly so that it is positioned against the upper portion 25 of the inclined edge 52 on hook 53.

When the filling nozzle is thus set for use, the depending tubular portion 11 thereof is inserted in a tank or container and the lower end of said tubular member may be arranged at different elevations by the engagement of the flange on the upper edge 30 of the filling nipple in any one of the notches 11a.

When the device has been thus set for use, 35 the attendant may leave the nozzle with the assurance that the valve therein will automatically close when the tank has been filled, or when the liquid delivered thereto rises to a predetermined level, and thus, 40 waste of the liquid due to accidental overflow will be prevented.

The liquid passing thru the nozzle discharges downwardly and outwardly thru the openings 24 and then, when the level of 45 the liquid discharged into the tank reaches the float 32 and moves the same upward, the pin and slot connections between rod 31 and fingers 44 will flex the upper portion of spring 43 outward, thereby disengaging dog 50 41 from the flange on collar 38 and the tension of spring 40 will move said collar upward a short distance, and the connections 36 and 37 between said collar and the spring 35 will flex the latter outwardly so as to 55 swing dog 34 on its axis and release collar 29, which will move upward under the influence of the relatively heavy spring 28.

As collar 29 is thus moved upward, it will 60 elevate the bifurcated forward end of lever 47, thereby swinging the same on its fulcrum and the rear end of said lever will move downward and bear against the inclined face 52 of hook 53, thereby disengaging the latter from the hook 55 and the spring beneath valve 15 will move the latter onto its

seat, thereby cutting off the further flow of liquid thru the spout and accomplishing the desired result.

In the event that it is desired to permit the valve 15 to close prior to the time that 70 the same is automatically closed, as just described, the attendant may press the plunger or pin 56 downward, thus engaging and moving downward the rear end of arm 47 and which action releases hook 53 from the 75 hook 55 and this will permit the valve 15 to close, as just described.

My improved filling spout, and particularly the type illustrated, is designed for use in filling the gasoline tanks of automobiles, 80 although said spout may be advantageously employed for filling any kind of tank or receptacle.

Thus, it will be seen that I have provided a filling spout that is relatively simple in 85 construction and which will act positively and automatically to cut off the flow of liquid thru the spout when the level of the liquid in the receiving tank reaches a predetermined point, thus eliminating possibility 90 of the receiving tank from overflowing, and which action, where gasoline is being dispensed, causes danger of fire.

It will be understood that minor changes in the size, form and construction of the 95 various parts of my improved filling spout may be made and substituted for those herein shown and described without departing from the spirit of my invention, the scope of which is set forth in the appended 100 claims.

I claim as my invention:

1. In a filling spout, a tubular member, a spring pressed valve for controlling the flow of liquid thru said tubular member, a handle pivotally mounted on the tubular member for unseating said valve, a latch for holding said handle in position to unseat said valve, an arm fulcrumed on the tubular member and adapted when moved in one 110 direction to disengage said latch, a spring pressed member against which one end of said arm normally engages, a latch for retaining said spring pressed member in set position and a float arranged for operation 115 in the discharge end of the spout for actuating said last mentioned latch.

2. In a filling spout, a tubular member, a spring pressed valve for controlling the flow of liquid thru said tubular member, a handle pivotally mounted on the tubular member for unseating said valve, a latch for holding said handle in position to unseat said valve, an arm fulcrumed on the tubular member and adapted when moved in one 125 direction to disengage said latch, a spring pressed member against which one end of said arm normally engages, a latch for retaining said spring pressed member in set position, a float arranged for operation in 130

the discharge end of the spout for actuating said last mentioned latch, and a spring held plunger carried by said handle for moving said arm into set position.

5. 3. In a filling spout, a tubular member having a depending portion at one end, a spring-held valve for controlling the flow of liquid thru said spout, a handle fulcrumed on the body of the spout and unseating said valve, a latch for retaining said handle in valve unseating position, an arm fulcrumed on the body of the spout and positioned below said handle, the rear end of which arm is adapted to engage said latch, 10 a spring pressed member arranged for operation in the upper portion of the depending end of the spout, which member bears against the under-side of the forward end of said arm, means for retaining said spring-held member in set position and a float arranged for operation in the lower portion of said depending member for releasing said retaining means.

4. In a filling spout, a tubular member 25 having a depending portion at one end, a spring-held valve for controlling the flow of liquid thru said spout, a handle fulcrumed on the body of the spout and unseating said valve, a latch for retaining said handle in valve unseating position, an arm fulcrumed on the body of the spout and positioned below said handle, the rear end of which arm is adapted to engage said latch, 30 a spring pressed member arranged for operation in the upper portion of the depending end of the spout, which member bears against the under-side of the forward end of said arm, means for retaining said spring-held member in set position and a float arranged for operation in the lower portion of said depending member for releasing said retaining means.

eration in the upper portion of the depending end of the spout, which member bears against the under-side of the forward end of said arm, means for retaining said spring-held member in set position, a float arranged for operation in the lower portion of said depending member for releasing said retaining means, and manually operable means for actuating said arm independent of the float actuated means.

5. In a filling spout, a tubular member 45 having a depending portion at one end, a spring-held valve for controlling the flow of liquid thru said spout, a handle fulcrumed on the body of the spout and unseating said valve, a latch for retaining said handle in 50 valve unseating position, an arm fulcrumed on the body of the spout and positioned below said handle, the rear end of which arm is adapted to engage said latch, a spring pressed member arranged for operation in 55 the upper portion of the depending end of the spout, which member bears against the under-side of the forward end of said arm, means for retaining said spring-held member in set position, a float arranged for operation 60 in the lower portion of said depending member for releasing said retaining means, manually operable means for actuating said arm independent of the float actuated means, and a manually operable plunger for moving 65 said fulcrumed arm into set position.

In testimony whereof I affix my signature.
MILTON R. HOLBERT.
